UNITED STATES PATENT OFFICE.

FRED MATHEWS, OF CHICAGO, ILLINOIS, ASSIGNOR TO CLINTON C. MURPHY, OF CHICAGO, ILLINOIS.

CARLINE.

1,161,498.

Specification of Letters Patent. Patented Nov. 23, 1915.

Application filed December 28, 1914. Serial No. 879,248.

To all whom it may concern:

Be it known that I, FRED MATHEWS, a citizen of the United States, and a resident of the city of Chicago, in the county of Cook and State of Illinois, have invented a new and useful Improvement in Carlines, of which the following is a specification.

This invention relates to metal carlines for freight car roofs, and particularly to 10 the end connections thereof.

The invention consists in a pressed steel bracket member for connecting the ends of a rolled or pressed steel carline to the side plates of the car.

15 Carlines are subjected to bending stresses throughout their length due to the weight of the roof, and to combined bending and twisting stresses at their ends caused by the continual straining and distortion of the car frame in service. The carline end connections to the side walls of the car must be such as to withstand these stresses. Rolled steel shapes which are suitable for the body portion of a carline are not well adapted 25 for the ends. A pressed steel carline may be formed to suitable shape at the ends, but the length of the carline differs with different makes of cars, and a large number of dies, jigs, templets, and similar tools are 30 required for making a complete line of sizes of pressed steel carlines to fit all cars if the end connections are made integral with the body portions.

The object of this invention is an end 35 bracket connection for a metal carline which is strong enough to resist the bending and twisting at the end of the carline, which is light in weight and which takes up but little room.

40 A further object is an end bracket connection which is adapted to be secured to the ends of pressed steel or rolled metal carlines of different lengths, whereby the body portion for each different length of carline can be formed with the same tools, and special dies for each different length of carline are dispensed with.

Further objects of the invention appear 45 hereinafter in connection with the description of the embodiment of the invention shown in the accompanying drawings; and what the invention consists in is particularly set forth in the appended claims.

In the drawings, in which the same char-

acters designate like parts in the several 55 views, Figure 1 is a plan view of the end of a carline and part of a side plate of a freight car, showing a bracket connection embodying the invention; Fig. 2 is a side view of the end of the carline and bracket connection shown in Fig. 1, the side plate being shown in cross-section; Fig. 3 is a top or 60 plan view of the bracket connection; and Fig. 4 is an inside face view of the same, showing the carline in cross-section. 65

The carline 11 shown in the drawings is channel or U-shape in cross-section, with outturned lateral flanges 12 along the tops of its side walls. The carline may be rolled, or pressed from sheet metal, and its ends are 70 cut off to make its length slightly shorter than the distance between the inside faces of the side plates of the car for which it is intended.

A bracket connection 13, which conforms 75 in shape across its middle to the under side of the carline at its ends, is riveted to each end of the carline. The bracket connection has flat top walls 14 which support the lateral flanges 12 of the carline, and a flat end 80 wall 15 which is riveted to the side plate 16.

The end wall is wider than the width of the carline, and the rivets for securing the bracket to the side plate are spaced apart sufficiently to afford a firm and substantial 85 connection between them. The edges of the top walls 14 and ends of the end wall 15 are turned downward and inward, forming marginal flanges 17 which extend across the angle between the top and end of the bracket 90 and stiffen its corners. The flanges 17 and U-shaped middle portion of the bracket 13 give it an effective form to resist bending and twisting.

The invention is not restricted to the precise forms and dimensions of the parts shown and described.

What I claim as my invention is as follows:

1. A carline having a channel-shape body 100 portion and end brackets secured thereto, each of said brackets having a top wall conforming throughout its length to the under side of the body portion of the carline and spreading laterally outside of the latter 105 at its end, and an end wall transverse to the carline and depending below the top wall of the bracket beyond the adjacent end of

said body portion, and inturned flanges along the side edges of the top wall and ends of the end wall connecting them across the outer corners of the bracket, whereby said carline is adapted to be embodied in existing cars without removing the roof.

2. A carline having a channel-shape body portion and end brackets secured thereto, each of said brackets having a flat top wall 10 gradually increasing in width from its inner to its outer end and provided with a middle depression conforming to the under side of the carline and an end wall transverse to the carline and coextensive with and depending 15 below the top wall of the bracket, said middle depression continuing through the end wall, said bracket also having inturned flanges along the side edges of the top wall and ends of the end wall constituting right 20 angle braces extending the length of the bracket and connecting said top and end walls at the outer corners of the bracket, and means for connecting said bracket to the

side plate arranged in the spaces between said inturned flanges and middle depression. 25

3. An end bracket for the carlines of freight cars, said bracket having a top wall and an end wall meeting at an angle, said top wall having a channel formed in its middle extending through the end wall for stiffening the bracket vertically under the end portion of a carline, said top wall being wider than said carline at the juncture with the end wall for stiffening said bracket laterally, and edge flanges turned in along the edges 30 of the top and end walls and forming vertical braces between the edges of said top and end walls and forming vertical braces between the edges of said top and end walls for stiffening said bracket against twisting. 35

Signed at Chicago, Illinois, this 23rd day of December, 1914.

FRED MATHEWS.
